UNITED STATES PATENT OFFICE.

WILLIAM WHITE, OF PHILADELPHIA, PENNSYLVANIA.

FIREPROOF CONSTRUCTION.

SPECIFICATION forming part of Letters Patent No. 663,204, dated December 4, 1900.

Application filed May 28, 1900. Serial No. 18,195. (No model.)

To all whom it may concern:

Be it known that I, WILLIAM WHITE, a citizen of the United States, residing in the city and county of Philadelphia, State of Pennsylvania, have invented a new and useful Improvement in Fireproof Construction, which improvement is fully set forth in the following specification and accompanying drawings.

My invention consists of improvements in a fireproof construction embodying arch-blocks having keys extending from the abutting edges thereof in opposite directions and adapted to engage oppositely-arranged keys on abutting arch-blocks.

15 It further consists in forming arch-blocks so that the same will break joint.

It further consists in providing means for locking the arch-blocks together.

Figure 1 represents a perspective view of 20 a portion of a fireproof construction embodying my invention. Figs. 2 and 3 represent perspective views of the arch-blocks employed. Fig. 4 represents a side elevation showing a different form of arch-block employed.

25 Similar letters of reference indicate corresponding parts in the drawings.

Referring to the drawings, A designates an arch-block which is formed with a curved 30 lower edge B and provided with the lugs or keys C and D, projecting from the abutting edge of said arch-block, the lug D being so arranged as to provide a shoulder E, upon which is adapted to rest a key of an abutting arch-block, the lug C being adapted to rest upon a projecting key similar to the key D of the abutting arch-block, it being seen that said keys are so arranged that the abutting arch-blocks break joint about midway, 35 allowing approximately the half of each arch-block to project on either side to receive the next abutting arch-block. Each arch-block is provided with the grooves F for the reception of the foot G of the I-beam H and is 40 provided with a projection J, one set of arch-blocks being provided with tongues K on said projection J and the others with grooves L in said projection J for the reception of the said tongues K of the next arch-block, it being noticed that said tongues K and grooves L 45 are beneath the beam H when in position.

One side of each arch-block is provided with a lug M, the opposite side of each arch-block having an opening N therein adapted to receive the said lug on the next side abutting 55 arch-block.

Embedded in the arch-block is a wire mesh P, having the ends Q of one set of wires projecting from the abutting ends of the arch-block and being flexible, and the ends R extending from the projection J and being flexible, it being seen that when the arch-blocks are in position the ends Q of the wires of abutting arch-blocks are twisted together, while the ends R of the wires are twisted, as 60 65 will best be seen at S, so that each series of arch-blocks are locked together at the abutting ends and at the lower ends to the next series of arch-blocks.

T designates a slot at the rear of the arch-blocks to permit concrete to pass thereinto and fill any grooves that may occur between the arch-blocks and the beams.

Each arch-block is provided with hooks or eyes U, to which are secured wires V, which 70 are also secured to the I-beams, forming a support or brace for the abutting ends.

The operation will be readily seen. The arch-blocks are placed so that the upper extending lug rests upon the shoulder formed 80 by the lower extending lug of the end abutting arch-blocks and so that the arch-blocks break joint, the projections entering the openings N in the next adjacent arch-blocks, the tongues K entering the grooves L beneath the 85 beam, while the ends Q and R of the wire mesh are twisted and locked and the wires V connected with the eyes U and the beam H, thus securely fastening the various parts together and preventing sagging or breaking 90 apart.

While I have shown the preferred form of arch-block employed, I do not desire to be limited in every instance to the exact construction as herein shown and described, for 95 in Figs. 1, 2, and 3 I have shown an arch-block with a grooved bottom, while in Fig. 4 I have shown a flat base, making a flat ceiling.

Having thus described my invention, what I claim as new, and desire to secure by Letters 100 Patent, is—

1. In a fireproof construction, arch-blocks,

a key extending from the abutting edge thereof at substantially the upper edge and adapted to rest upon a key on the next abutting block and a key extending over substantially the lower edge upon which another key of another abutting arch is adapted to rest.

2. In a fireproof construction, an arch-block, a key extending from the abutting face thereof near the upper edge and adapted to rest upon a key on an abutting arch-block, a key extending near the lower edge thereof, upon which a key of another abutting arch-block is adapted to rest, and said arch-blocks being so arranged as to break joint with the abutting arch-block.

3. In a fireproof construction, an arch-block having a lug or key extending from substantially the upper edge of the abutting face thereof and a lug or key extending from substantially the lower edge of the abutting face, a groove adapted to receive the foot of an I-beam, a projection on said arch-block which is provided with a groove adapted to receive a tongue on the next arch-block.

4. In a fireproof construction, an arch-block having a key extending from the abutting face thereof at substantially the upper portion and a key extending from said abutting face at substantially the lower portion thereof, a lug projecting from one side thereof and an opening in the other side.

5. In a fireproof construction, arch-blocks provided with oppositely-extending lugs, means for locking said arch-blocks with respect to the next abutting arch-block, and means embedded in each of the said arch-blocks for connecting one with the other.

6. In a fireproof construction, an I-beam, an arch-block, a key extending from the abutting face thereof, and a key from the abutting face below the first-mentioned key at one side thereof, and means connected at or near the abutting edge of said arch-block with said I-beam for supporting said arch-block.

7. In a fireproof construction, arch-blocks so arranged as to break joint, and a wire mesh embedded in said arch-blocks, so arranged as to have projecting ends which can be secured to the next abutting arch-blocks.

8. In a fireproof construction, arch-blocks suitably constructed, each having one end adapted to rest upon the foot of an I-beam, keys on the abutting edges of said arch-blocks, and tie rods or wires connected with the forward ends of said arch-blocks and to said I-beam.

9. In a fireproof construction, an arch-block having keys extending at varying heights from the abutting edge thereof and out of vertical alinement and engaging with oppo-

sitely-extending keys on two abutting arch-blocks.

10. In a fireproof construction, a beam, an arch-block supported thereby, and means projecting from said arch-block which is adapted to enter a groove in the next abutting arch-block below said beam.

11. In a fireproof construction, beams, arch-blocks and means connected at or near the abutting edges of said arch-blocks and with said beams for supporting said arch-blocks.

12. In a fireproof construction, arch-blocks, means on the abutting face thereof whereby a portion of an arch-block rests upon a portion of the adjacent arch-block and means out of vertical alinement with the first-mentioned means and on the same abutting face whereby a portion of said first-mentioned arch-block serves as a support for an adjacent arch-block.

13. In a fireproof construction, an arch-block having a key extending therefrom with its abutting face pointed downwardly, and a second key extending from said block out of vertical alinement with said first-mentioned key and at a different height and having its abutting face pointed upwardly.

14. In a fireproof construction, an arch-block having means on its abutting face for engagement with the next abutting arch-block, a groove adapted to receive the foot of an I-beam, a projection on said arch-block which is provided with a groove adapted to receive a tongue of the next arch-block.

15. In a fireproof construction, an arch-block having means on its abutting face for engagement with the next abutting arch, a groove adapted to receive the foot of an I-beam, a projection on said arch-block provided with a tongue and adapted to enter a groove in the next arch-block.

16. In a fireproof construction, an arch-block having a key extending from the abutting face thereof at substantially the upper portion and a key extending therefrom at substantially the lower portion, a lug projecting from one side thereof, an opening in the other side and said arch-block being so arranged as to break joint with the abutting arch-blocks when in position.

17. In a fireproof construction, an I-beam, arch-blocks, means on the abutting faces thereof for engagement with the next arch-blocks, and means connected at or near the abutting edges of said arch-blocks and with said I-beams for supporting said arch-blocks.

WILLIAM WHITE.
